FIG. 6.

INVENTOR.
HANCI CORDREY.
BY *A.B. Bowman*
ATTORNEY

UNITED STATES PATENT OFFICE.

HANCIL CORDREY, OF CHULA VISTA, CALIFORNIA.

SAFETY-RAZOR-BLADE HOLDER FOR STROPPING SAFETY-RAZOR BLADES.

Application filed January 16, 1923. Serial No. 612,883.

My invention relates to holders for safety razor blades for holding the blades for sharpening the same and the objects of my invention are: first, to provide a holder which is applicable for holding the different makes of safety razor blades now in use while stropping the same; second, to provide a simple holder and handle member which is adapted and applicable for holding Duplex, Gillette, Gem, Ever Ready, Enders and other makes of blades without change; third, to provide a holder of this class which is very simple of application to the various makes of blades; fourth, to provide a holder of this class which is very simple and economical of construction, durable, easy to operate, efficient and which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawings, and to the characters of reference thereon, which form a part of this application, in which:

Figure 1, is a side elevational view of my holder, showing a Gillette razor blade which is rigidly positioned therein ready to be sharpened on a strop or the like; Fig. 2 is an edge view at a right angle to that of Fig. 1; Fig. 3 is an end view thereof; Fig. 4 is a side elevational view of the holder with a Gem safety razor blade positioned therein ready to be sharpened; Fig. 5 is an end view thereof; Fig. 6 is a side elevational view of said holder with an Ever Ready safety razor blade positioned therein ready to be sharpened and Fig. 7 is an end view thereof.

Similar characters of reference refer to similar portions throughout the several views of the drawings.

My holder consists of a piece of round wire about three sixteenths of an inch in diameter formed into a loop at the middle 1^a and enlarging gradually at 1^b forming a handle then gradually converging till the extended ends engage each other at 1^c, as shown best in Figs. 1 and 6 of the drawings, then extend for some distance in engagement with each other, the extended ends being tapered at 1^d. These two extended members are provided with narrow slots 2 in their

extended ends of a width of approximately the thickness of the blade to be held and so formed that the ends tend to close together. These slots are preferably made by sawing and then are forced together partially closing these slots and the ends are provided with beveled portions 1^e adapted to facilitate the insertion of the blade at the end.

It is preferred to make this holder of wire of sufficient carbon to make it sufficiently resilient so that it would apply itself to slightly different thicknesses of blades and the ends of the slots 2 tend to close at all times when the blades are not therein so that when the blade is positioned therein, as shown in Figs. 1, 2, and 3 in the form of a Gillette blade there is sufficient friction between the surface of the blade and the sides of the two slots so that the blade is clamped and held securely positioned for stropping. And when a blade, for instance with a back like the Gem blade is positioned therein, the plate is only mounted in the one slot in one member and the back portion is positioned between the two ends, the ends being spread, which secures the blade surface securely between the two members and the blade positioned in one of the slots.

In case it is desired to sharpen a blade with a sharpened end on one edge only and without a back, the blade the same thickness throughout as the Ever Ready as shown in Fig. 6, the blade is positioned in one of the members so that its back edge rests against the other member, the spring of the other members closing the slot partially so that the blade will not enter the slot in the other member and forms the back for the same.

Though I have shown and described a particular construction, I do not wish to be limited to this particular construction but desire to include in the scope of my invention, the construction, substantially as set forth in the appended claims.

It is obvious that with this holder there is provided a means for holding a great variety of different makes of safety razor blades without changing the device; that the device is very simple to manufacture, easy to apply to the different makes of blades, efficient and durable.

Having thus described my invention what I claim as new and desire to secure by Letters Patent, is:

1. A safety razor blade holder, including

a metallic member bent intermediate its ends forming a loop and its extended ends parallel with each other and slotted from side to side providing an alined slot through both ends, adapted to receive a safety razor blade and support the same by the inherent spring of the metal only.

2. A safety razor blade holder, including a metallic member bent intermediate its end 10 forming a loop and its extended ends parallel with each other and slotted from side to side providing an alined slot through both ends adapted to receive a safety razor blade and support same.

15 3. A safety razor blade holder, including a piece of spring wire formed into a loop intermediate its ends and its opposite ends contiguous to and parallel with each other, and provided with slots extending through 20 both of said ends and conforming with each other adapted to receive and hold a razor blade by the inherent spring of the member whereby it may be readily removed.

4. A safety razor blade holder formed of 25 a single piece of spring wire having a loop intermediate its ends and the ends positioned adjacent and substantially parallel with each

other, each of said ends being slotted from side to side providing slots aligned with each other through both ends of the holder, the 30 loop portion of said holder providing resilient means for forcing the ends of the holder toward each other, said holder being adapted for holding a flat razor blade or for holding a razor blade having an enlargement at one edge.

5. A safety razor blade holder formed of a single piece of spring wire having a loop intermediate its ends and having a slot in one end, the plane of the slot extending 40 through the other end of the holder, the loop portion of said holder providing resilient means for forcing the ends of said holder toward each other, the one end of the holder provided with a slot being adapted to receive a safety razor blade and the other end of the holder being adapted to clamp an enlarged portion at one edge of the razor blade against the end of the holder provided with a slot.

In testimony whereof, I have hereunto set my hand at San Diego, California, this 9th day of January, 1923.

HANCIL CORDREY.
